UNITED STATES PATENT OFFICE.

JACOB HALLECK ZINN, OF INDIANAPOLIS, INDIANA.

SEWER CONSTRUCTION.

932,743.

Specification of Letters Patent. Patented Aug. 31, 1909.

Application filed July 24, 1908. Serial No. 445,251.

To all whom it may concern:

Be it known that I, JACOB HALLECK ZINN, a citizen of the United States, residing at Indianapolis, in the county of Marion and 5 State of Indiana, have invented new and useful Improvements in Sewer Construction, of which the following is a specification.

This invention relates to sewer construction, the object of the invention being to 10 provide sewer construction which will be more sanitary than the ordinary cement sewers now extensively used and at the same time less expensive and capable of easier and more rapid installation, the completed sewer 15 being practically continuous or unbroken from end to end, or in other words, without any open joints therein.

With the above and other objects in view, the nature of which will more fully appear 20 as the description proceeds, the invention consists in the novel construction, combination and arrangement of parts as herein fully described, illustrated and claimed.

In the accompanying drawings:—Figure 25 1 is a vertical cross section through a sewer embodying the present invention. Fig. 2 is a vertical longitudinal section through the same showing the manner of uniting adjoining sections. Fig. 3 is a perspective view of 30 one of the sewer sections. Fig. 4 is a detail vertical cross section showing the means for causing the sewer sections to drain off water during installation. Fig. 5 is a vertical cross section showing a modified form of 35 section.

The construction of the sections of the sewer is best illustrated in Fig. 3 in which one of the sections is shown in detail wherein it is seen to comprise a cylindrical body 1 and a base 2, the base forming a reinforcement 40 for the body 1 and in the preferred embodiment of the invention comprising a flat supporting bottom 3. At the opposite sides the base extends partially upward 45 along the sides of the body and is made sufficiently thicker than the body to provide oppositely located shoulders or ledges 4 which extend lengthwise of the section and provide a support for a body of concrete indicated 50 at 5.

The concrete body 5 may be composed of any usual composition such as Portland cement, sand and gravel or crushed stone, while the body 1 and base 2 of the sewer 55 sections are preferably composed of vitrified clay, which is salt glazed so as not to admit

of the lodging or adherence thereto of sediment. It will also be observed by reference to Figs. 2 and 3 that the base 2 is extended at one end beyond the corresponding end of 60 the body 1 to form a stay or socket 6 to receive the adjacent end of the adjoining section, the body of which projects beyond the base as shown at 7. In this way the sections of the sewer overlap each other or more 65 accurately speaking, the body portion of one section overlaps the base portion of the adjoining sections thus attaining an accurate alinement of all of the sections. The outer coating 5 is applied to the sections 70 after the same have been placed in the ditch and combined in the manner above described, an outer incasing shell or jacket of any suitable material being employed in connection with the sewer sections to enable the 75 concrete while in a plastic condition to be introduced between the body 1 and said outer shell or jacket, it being understood that when the concrete has hardened sufficiently, the said outer shell or jacket is removed. As said outer shell or jacket forms 80 no part of the present invention, the same has not been shown.

It is also within the scope of this invention to make the base 2 of sufficient depth 85 and other dimensions to provide for the formation therein of one or more drain channels 8 in the installation of the sewer and carrying off of the water in the bottom of the drainage while the construction is in 90 progress.

By means of the construction described, a sanitary sewer is produced as by reason of the interior of the sections being salt glazed or of vitrified clay there is little liability of 95 cement or other refuse lodging in or adhering to the inner surface thereof. The construction described also greatly facilitates the building of the sewer as a whole as the sections form cores or formers around which 100 the concrete is laid and when the sewer is complete, it is practically continuous or without joints from one end of the line to the other. Furthermore, the weight of the 105 sewer sections is approximately only about one-half the weight of the sewer pipe section now in common use which admits of the same being manufactured more economically and handled with greater ease at all points.

By reason of the outer layer or coating of cement extending from shoulder to shoulder

and continuously across the joints between the adjoining sections, such layer or coating acts as a reinforcing and strengthening medium for the vitrified clay sections, holding the same in perfect alinement. The base or invert may be made separate from the remainder of the sections where conditions demand it for convenience in handling, the base or invert being placed in the ditch and 10 the tubular body being then placed upon the base or invert in readiness for the concrete coating or reinforcement.

I claim:

1. A sewer pipe section comprising a hollow cylindrical body and a base integral therewith, the inner wall of the base being coincident with the inner wall of the body and the base being of greater thickness than the body at the junction of the body and

base to provide offset longitudinally extending shoulders.

2. A sewer pipe section comprising a tubular body, and a relatively thick base integral with the body forming offset longitudinal shoulders opposite the juncture of the body and base, said shoulders projecting outward beyond the plane of the body, the base being extended at one end beyond the body to form a seat or socket for an adjoining section, and the body being extended 30 at the other end beyond the base for a like purpose.

In testimony whereof I affix my signature in presence of two witnesses.

JACOB HALLECK ZINN.
